UNITED STATES PATENT OFFICE.

FREDERICK VOLK, JR., OF NEW YORK, N. Y.

WIRE-STRETCHER.

SPECIFICATION forming part of Letters Patent No. 611,297, dated September 27, 1898.

Application filed April 2, 1898. Serial No. 676,223. (No model.)

To all whom it may concern:

Be it known that I, FREDERICK VOLK, Jr., a citizen of the United States, residing at New York city, in the State of New York, have invented a new and useful Wire-Stretcher, of which the following is a specification.

My invention relates to clamps or grippers for stretching wires such as are used for fences or telephone or telegraph lines.

The object of my invention is to produce an extremely cheap, powerful, and convenient clamp of this class which affords an extensive bearing-surface for the wire and exerts a pressure thereon corresponding with the amount of power applied in stretching.

With this object in view my invention consists in a wire-clamp comprising a main plate provided with a side extension forming what may be termed the "stationary" jaw of the clamp and with a longitudinal slot in its outer end, a lever pivoted to the main plate and provided with a movable jaw adapted to contact with the fixed jaw, a pitman connecting-rod pivotally secured to the outer raised end of the pivoted lever, a pin passing through the outer lower end of the pitman or connecting rod and through the slot in the main plate, and a clevis connected at its ends upon the pin.

My invention further consists in a windlass-pulley to be used in connection with my improved clamp.

My invention further consists in the improved construction, arrangement, and combination of parts hereinafter fully described and afterward specifically pointed out in the appended claims.

In order to enable others skilled in the art to which my invention most nearly appertains to make and use the same, I will now proceed to describe its construction and operation, reference being had to the accompanying drawings, forming part of this specification, in which—

Figure 1 is a perspective view illustrating a clamp constructed in accordance with my invention, the parts being in the position they assume when in operation. Fig. 2 is a view in side elevation, illustrating the clamp in full lines in its open position and in dotted lines in its closed position. Fig. 3 is a top plan view of the clamp in its closed position,

part of the clevis being broken away. Fig. 4 is a top plan view of the windlass-pulley to be used in connection with my clamp for stretching wire.

Like letters of reference mark the same parts wherever they occur in the different figures of the drawings.

Referring to the drawings by letters, A is the main plate, which is provided on one side with an extension or block B, which forms the stationary jaw, and is provided with teeth on its upper edge. The main plate is also provided with a longitudinal slot C in its outer edge.

D indicates a lever pivoted to the side of the main plate A at one end by means of a pin E, said plate D having a downward extension at F to form the movable jaw, said extension being provided with teeth to correspond with the teeth of the fixed jaw B. The outer end G of the lever D is upwardly inclined, and a pitman or connecting rod H is pivotally connected to its outer end by means of a pin I. A pin J passes through the lower end of the pitman or connecting rod H and through the slot C and has mounted upon each end the ends of a clevis K.

In stretching wire the jaws B and F are opened by pushing the pin J toward the inner end of the slot C, a suitable wire or rope from a stretching means or a towing-line being connected in the clevis K. The wire is inserted between the jaws when in their open position and the line attached to the clevis K is pulled. This operation first draws the pin J toward the outer end of the slot C, carrying the connecting-rod H with it and drawing down the lever D and movable jaw F until the wire is firmly clamped between the two jaws. A further pulling upon the line will stretch the wire to any desired degree of tension.

My device is especially useful to fence-builders and linemen of telephone and telegraph companies and in fact in any business where wire is required to be stretched.

The construction is extremely simple and the operation sure and reliable, inasmuch as the greater the pull the tighter the jaws clamp the wire.

In the operation of my clamp the line (not shown, but hereinbefore referred to as con-

nected to the clevis K) may be wound upon a pulley L, (see Fig. 4,) pivotally mounted in a U-shaped metallic frame M and provided on one end, which projects beyond the frame, 5 with a ratchet-wheel N and a pawl O, which is pivoted to one side of the U-shaped frame and has its point in engagement with the teeth of the ratchet-wheel N to permit of its free turning in one direction, but preventing 10 its turning in the opposite direction. Secured to the U-shaped frame M is a hook P, and upon the opposite projecting end Q of the pivot of the pulley L is a suitable crank or handle to be used to turn the pulley. In use 15 this device, in connection with the hook P, is engaged with any suitable rigid structure, and the rope before referred to is connected with the clevis K, secured upon the pulley L. By turning the pulley in the proper direction 20 with reference to the ratchet-wheel the rope will be wound thereupon and stretched to an extreme degree of tension, exerting its power at its outer end upon the clevis K and through the medium of the connecting-bar H upon the movable jaw of the clamp.

While I have illustrated and described what I now consider to be efficient means for carrying out my invention, I do not wish to 25 be understood as restricting myself to the exact details of construction shown and described, but hold that such slight changes or variations as might suggest themselves to the

ordinary mechanic would properly fall within the limit and scope of my invention. 35

Having thus fully described my invention, what I claim as new, and desire to secure by Letters Patent of the United States, is—

1. A wire-clamp consisting of a stationary plate provided with a side extension forming the fixed jaw and with a longitudinal slot in its outer end; a lever pivoted to the outer end of the main plate provided, between its ends, with a movable jaw adapted to engage the fixed jaw, a connecting-rod or pitman pivoted secured to the outer upper end of the pivoted lever, a pin passing through the outer lower end of the connecting-rod and the slot in the main plate, and a loop or clevis connected with said pin, substantially as described. 45

2. A windlass - pulley herein described, mounted at one end of a U-shaped metallic frame, and to the other end a suitable hook attached for securing the frame to a fixed object; on one end of the axis of the pulley, a ratchet-wheel mounted with a pawl pivoted to the side of the U-shaped frame and engaging the teeth of the ratchet-wheel, and the other end of the axis of the pulley formed to receive a crank or handle for turning the pulley, substantially as described. 55
